Primary Examiner — Sheryl Lane*Assistant Examiner* — Ieisha Price(74) *Attorney, Agent, or Firm* — Bereskin & Parr LLP/S.E.N.C.R.L., s.r.l.(57) **CLAIM**

The ornamental design for a building panel mid clip, as described and shown.

DESCRIPTION

FIG. 1 is a perspective view of a building panel mid clip showing our new design;

FIG. 2 is a front elevation view of the building panel mid clip shown in FIG. 1;

FIG. 3 is a right side elevation view of the building panel mid clip shown in FIG. 1;

FIG. 4 is a rear elevation view of the building panel mid clip shown in FIG. 1;

FIG. 5 is a left side elevation view of the building panel mid clip shown in FIG. 1;

FIG. 6 is a top plan view of the building panel mid clip shown in FIG. 1; and,

FIG. 7 is a bottom plan view of the building panel mid clip shown in FIG. 1.

All portions of the building panel mid clip located between the break lines, shown throughout the drawing disclosure, form no part of the claimed design.
